CHEMICAL LABORATORY APPARATUS

William O. Geyer, Bloomfield, N. J.

Application July 13, 1933, Serial No. 680,195

4 Claims. (Cl. 23—259)

This invention relates to stop-cocks and more particularly to three-way stop-cocks for use in combination with a source of fluid supply and a container into which the fluid is to be drawn and from which it is to be drained through the one stop-cock. Still more particularly this invention relates to glass stop-cocks of the three-way type to be used in combination with a graduated tube, forming thereby chemical apparatus known in the art as a burette of the so-called self-filling type.

One of the objects of the present invention is to provide an improved three-way stop-cock.

Another object of the present invention is to provide an improved self or automatically filling burette.

Still another object of the present invention is to generally facilitate the transfer of fluid from a fluid source to a container and the withdrawal of said fluid from the container through a single stop-cock.

Other objects and advantages will be apparent as the invention is more fully hereinafter disclosed.

25 In accordance with the objects of the present invention I have devised a new type of three-way stop-cock for use in combination with a graduated tube or other container whereby the transfer thereto of fluid from a supply source and the withdrawal of fluid from the container through a single stop-cock may be greatly facilitated. As a specific embodiment of the present invention I will describe the same as it may be utilized in combination with a graduated tube 30 of the type known in the chemical glassware art as a titrating burette whereby an improved burette of the self-filling type is obtained. It is not to be construed, however, that I am to be limited thereby, as the three-way stop-cock of 35 the present invention is adapted to a plurality of uses and applications which will be apparent from a description of the specific embodiment thereof.

Before further disclosing the nature and scope 40 of the present invention reference should be made to the accompanying drawing, wherein

Fig. 1 is a side elevational view of the self-filling burette of the present invention;

Fig. 2 is a sectional side elevation view showing the stop-cock plug in the re-fill position;

Fig. 3 is a second view of the same showing the stop-cock plug in the discharge position; and

Fig. 4 is a perspective view of the stop-cock plug illustrating that feature of the present invention.

Referring to the drawing, the three-way stop-cock of the present invention in the specific embodiment described therein is comprised essentially of glass and consists of a barrel 1, having an inner conically tapered surface and a conically tapered plug 2, adapted to form a tight joint therewith. Upon the outer face of barrel 1 are positioned a pair of longitudinally spaced conduits 3 and 4 extending through the barrel and opening to the conically tapered inner surface thereof. Upon one of said conduits 4 is positioned a container 5 which in the specific embodiment is a graduated tube 5 (Fig. 1) comprising the fluid measuring means or burette and to the other of said conduits 3 is connected the source of fluid supply (not shown) for the said graduated tube 5. It is usual to position the source of fluid supply at a level above the graduated tube 5 so that a gravity feed therefrom to the conduit 3, to which it is connected, can be obtained.

60 Means are provided in plug 2 to permit fluid from the supply source (not shown) to flow from the spaced conduit 3, to which it is connected, into the other conduit 4, when it is desired to fill the graduated tube 5 connected thereto. In accordance with the present invention this means comprises a longitudinal groove 6 in the surface of plug 2, having a length adapted to bridge the gap between the spaced conduits 3 and 4.

65 Means also are provided to discharge fluid from the graduated tube 5 through the plug 2. This means comprises a bore passageway 7 extending diametrically and angularly through the plug 2, having one end opening in the groove 6 at a point 70 aligning it with the said conduit 3 and the opposite end thereof opening at the plug surface on the side opposite to the groove 6 in a position so that upon a 180 degree rotation of the plug 2, by means of handle 10, the said opposite end of said bore passageway will align with spaced conduit 4.

75 Means also are provided to permit the fluid from graduated tube 5 to discharge through the barrel 1 when the plug 2 has been so rotated, which comprises a drain conduit 8 preferably 80 provided with a capillary tip 9 extending through the barrel to the inner surface thereof, which conduit 8 is located on said barrel 1 diametrically opposite to the pair of conduits 3 and 4 and in substantial alignment with conduit 3.

85 When it is desired to interrupt the flow of fluid either into or out of the graduated tube 5 plug 2 may be given a quarter turn rotation in either direction.

90 The three-way stop-cock of the present invention.

tion has many advantages over three-way stop-cocks of the prior art which have heretofore been used in combination with a graduated tube or burette. In the prior art stop-cocks two bore 5 passageways are provided through the plug 2, one of which serves as a fluid discharge passageway from the graduated tube 5 and the other of which serves as a fluid feed passageway for refilling the said graduated tube 5. In such a type stop-cock 10 the supply conduit had to be positioned on the bottom of the stop-cock adjacent the discharge conduit 8, thereby materially interfering with the use and manipulation of the said stop-cock. The present structure eliminates these disadvantages 15 of such prior art stop-cocks thereby improving the burette of the self or automatically filling type.

Whereas, as a specific embodiment, I have described a three-way stop-cock comprised of glass 20 it is apparent that I am not to be limited thereby. Such a stop-cock constructed in accordance with the teachings of the present invention may be comprised of porcelain, metal, or other similar materials heretofore employed in the manufacture of stop-cocks without departing essentially from the scope of the present invention.

Whereas, also as a specific embodiment, I have illustrated the combination of the stop-cock with a graduated tube of the burette type, it is also apparent that I am not to be limited thereby. Such a stop-cock as is herein described is adapted for wide commercial use with all types of containers 30 wherein it is desired to transfer fluid from a supply source to the container and to withdraw fluid 35 from the container through the same stop-cock.

It is apparent therefore that many modifications and adaptations of the specific embodiment of the present invention may be made therein without departing essentially from the nature and 40 scope thereof, but all such modifications and adaptations are contemplated as may fall within the scope of the following claims:—

What is claimed is:

1. A three-way stop-cock comprising a barrel 45 having an inner surface conically tapered from one end of said barrel to the other, a pair of longitudinally spaced conduits on said barrel and opening there through to the inner conical surface thereof, a single conduit positioned on said 50 barrel diametrically to said pair of conduits and having an opening there through diametrically aligned with the opening of the lower of said pair

of conduits, and a conically tapered plug member adapted to seat internally in said barrel, said plug member having a longitudinally extending groove in the surface thereof, said groove being adapted to bridge the openings of said pair of conduits, 80 and a bore passageway extending diametrically there through from the lower end of said groove towards the upper end of said plug and opening at the opposite surface thereof at a point diametrically opposite the upper end of said groove. 85

2. A three-way stop-cock comprising a barrel section having a conically tapered inner surface, a pair of longitudinally spaced conduits on one side thereof opening through said barrel to the inner surface thereof, a single conduit on the diametrically opposite side of said barrel and opening through said barrel to the inner surface thereof, and a conically tapered plug member for said barrel, said plug member having a longitudinally extending groove in the surface thereof adapted to bridge the gap between the openings of the said pair of conduits on the inner surface of said barrel to provide a passageway there between along the said plug member, and having a bored passageway extending angularly and diametrically through the said plug member, from one end of the said groove at a point aligning it with one of the openings of said pair of conduits to a point on the plug surface adapting it to align with the opening of the other of said pair of conduits, when said plug is rotated about its axis approximately 180 degrees, the said single conduit being disposed on said barrel with respect to the said bored passageway to align with the passageway opening in the said groove when the 100 said plug member is in its said rotated position. 105

3. In combination a three-way stop-cock of the type described and claimed in claim 1, and a container attached to the upper of said pair of conduits and positioned above the said stop-cock, 115 the lower of said pair of conduits being adapted to be connected to a source of fluid to be supplied to said container.

4. A self-filling burette comprising in combination a three-way stop-cock of the type described 120 and claimed in claim 1 and a graduated tube attached to the upper of said pair of conduits and positioned above the said stop-cock, the lower of said pair of conduits being adapted to be connected to a source of fluid to be supplied to said 125 graduated tube.
